UNITED STATES PATENT OFFICE.

JOHN HAYS HAMMOND, JR., OF GLOUCESTER, MASSACHUSETTS.

RECEIVING SYSTEM FOR RADIANT ENERGY.

Application filed October 17, 1917. Serial No. 197,127.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Receiving Systems for Radiant Energy, of which the following is a specification.

10 In the operation of some of the receiving systems for radiant energy which have been heretofore designed for use upon a torpedo for steering the torpedo from a distance, it has been found that the receiving system 15 some times fails to respond properly to the signals from a distant station when the torpedo is in close proximity to a hostile station which is transmitting powerful signals or shocks for the purpose of interfering with 20 the control of the torpedo from the distant station. It has been found that this failure on the part of the receiving system to respond properly to the signals from a distant control station is sometimes due mainly to a 25 "smothering" or "saturating" effect which is produced by the powerful signals from the hostile station, which prevent the weaker signals from the distant control station from having any appreciable effect upon the receiving system.

30 One of the objects of this invention, therefore, is to provide a receiving system, which will not be liable to be "smothered" or "saturated" by signals transmitted from a hostile station. Other objects of this invention are to provide an improved detector, and to provide other improvements, as will appear hereinafter.

35 In the accompanying drawings, Fig. 1 is a diagrammatic side elevation of a receiving system including an ordinary gaseous detector such as is sometimes provided in receiving systems of radiant energy which are used in controlling torpedoes; Fig. 2 is a diagram 40 explanatory of the operation of the detector shown in Fig. 1; Fig. 3 is a diagrammatic side elevation of a receiving system constructed in accordance with this invention; Figs. 4 and 5 are diagrams explanatory of 45 the operation of the receiving system shown in Fig. 3; and Figs. 6 and 7 are diagrammatic side elevations respectively of two modified receiving systems constructed in accordance with this invention.

50 The ordinary receiving system, shown in Fig. 1, comprises a gaseous detector 9 of any

well known form, including a vacuized glass bulb 10 in which are arranged a plate or terminal 11, a grid element or potential gradient changing means 12, and a filament or 60 ionizing means 13. The filament 13 is arranged to be heated by a battery 15, one pole of which is connected to one end of the filament 13 by a conductor 16, and the other pole of which is connected to the other end 65 of the filament 13 through a rheostat 17. The detector 9 is arranged to control a plate or wing circuit 20, which connects the plate or terminal 11 with one end of the filament 13, and which is arranged to be energized by a 70 battery 21 and to control a receiving instrument 22 or other device. The detector 9 is usually arranged to be controlled by a closed oscillatory circuit, including a variable condenser 25 and a coil 26, one end of which is 75 connected by a conductor 27 to the grid 12, and the other end of which is connected by a conductor 28 to one end of the filament 13.

In the form of receiving system shown in Fig. 1, the coil 26 is inductively connected to 80 a coil 29 which forms part of an open aerial circuit, including an antenna 30 and being grounded through the coil 29 as at 31.

In the ordinary arrangement of receiving system shown in Fig. 1, the effect of an incoming signal received by the open aerial circuit 30, 29, 31 is to cause the potential of the grid 12 to fluctuate with respect to the potential of the filament 13, and thereby to cause corresponding fluctuations in the current which is normally flowing in the controlled circuit through the bulb 10, the battery 21 and the controlled instrument or device 22.

A characteristic plate current-grid voltage 95 curve 40 showing diagrammatically the operation of the ordinary gaseous detector 9 appears in Fig. 2 in which the curve 40 is plotted from two full lines 41 and 42 which form a right angle, and along one of which, 100 41, the current flowing through the plate or controlled circuit 11, 20, 22, 21, 13, is measured, and along the other of which, 42, the voltage on the grid 12 is measured. In practice, the voltage of the grid 12 is adjusted 105 to be normally either approximately as indicated by the point where the dotted line 45 intersects the full line 42, or approximately as indicated by the point where the dotted line 46 intersects the full line 42, 110 with corresponding normal currents indicated respectively by the points where the

dotted lines 47 and 48 intersect the full line 41.

In other words, the voltage of the grid is adjusted approximately either at the voltage indicated by one of the "humps" of the characteristic curve 40, or approximately at the voltage indicated by the other "hump" of the characteristic curve 40. The effect of an incoming signal in either case is to cause a symmetrical fluctuation of the potential of the grid 12 on either side of its normal potential, and such symmetrical fluctuations of the voltage of the grid cause unsymmetrical fluctuations of the current in the controlled circuit 20, 21 of the detector.

Such unsymmetrical current fluctuations are in effect rectifying actions, and when the grid 12 is normally adjusted at the lower initial voltage indicated by the line 45 of Fig. 2, an incoming signal of radiant energy acts upon the detector 9 to cause a net increase in the current through the detector and the controlled circuit 20, 22, 21, while when the grid 12 is normally set at a higher initial voltage indicated by the line 46 of Fig. 2, an incoming signal acts upon the detector to cause a net decrease in the current through the detector and the controlled circuit 20, 22, 21.

In either case, as the strength of the incoming signal is increased, the current fluctuations through the detector and the controlled circuit 20, 22, 21 will eventually reach a limit imposed by the difference between the minimum and the maximum current indicated by the characteristic curve 40 of the detector. A further increase in the signal strength beyond this limit will no longer cause a corresponding net change in the current of the controlled circuit 20, 22, 21.

When the gaseous detector is in this condition, due for instance to forcible interference, it is evident that any weaker signal of radiant energy received at the same time cannot truly manifest itself in a corresponding change in the current of the controlled circuit 20, 22, 21, and hence could not well be "picked out" by even the most selective tuning devices operating from or controlled by the receiving device 22 of the controlled circuit 20, 22, 21. In other words, when the gaseous detector 9 is in this "smothered" or "saturated" condition, it cannot faithfully reveal in the current fluctuations of the controlled circuit 20, 22, 21, all the potential fluctuations of the incoming signals.

This invention provides a system in which the arrangement is such that it is extremely difficult, if not impossible, to "smother" or "saturate" the system through the action of powerful incoming signals from a relatively near interfering station in such a manner as to prevent the system from being properly responsive to the weaker signals from the distant control station. In one form of sys-

tem constructed in accordance with this invention, instead of having a single detector arranged to control the first receiving device or controlled circuit, a plurality of detectors 100, 101 and 102 of any suitable or well known construction, but preferably in the form of a plurality of gaseous detectors constructed as hereinbefore described, are arranged to be simultaneously controlled in any suitable manner and to act in unison to control a suitable receiving instrument or any desired arrangement of tuned receiving circuits.

For instance, as shown in Fig. 3, three detectors 100, 101, 102, may be arranged in accordance with this invention, to be controlled simultaneously by a closed oscillatory circuit including a variable condenser 105 and a coil 106. The coil 106 forms the secondary of a transformer 107, which has a primary coil 108 connected in series with an antenna 109 which is grounded through the coil 108 at 110. One end of the secondary coil 106 of the closed oscillatory circuit 105, 106, is connected by a conductor 120 to the three grids 12 of the detectors 100, 101, 102, and the other end of the secondary coil 106 is connected by a conductor 121 to one end of the filament 13 of the first detector 100, which in turn is connected by a conductor 122 to one pole of a battery 123, the other pole of which is connected by a conductor 124 to one end of the filament 13 of the second detector 101. This second filament 13 is connected in turn by a conductor 125 to one pole of a battery 126, the other pole of which is connected by a conductor 127 to one end of the filament 13 of the third detector 102. This latter filament 13 is connected by a conductor 128 to one pole of a battery 129 which is in a controlled circuit which includes a receiving device 130, and a conductor 131 connected to the three plates 11 of the three detectors 100, 101, 102. In this arrangement, the three plates 11 and the three grids 12 are connected in parallel, and the three filaments 13 are arranged so as to differ in potential from each other in progressively increasing amounts.

The three characteristic plate current-grid voltage curves 150, 151 and 152 of the three separate detectors 100, 101 and 102 arranged as shown in Fig. 3, are shown in Fig. 4, in which the curves are plotted from two straight full lines 153 and 154 which meet to form a right angle, and along one of which, 153, grid voltages are measured, and along the other of which, 154, plate currents are measured. The characteristic plate current-grid voltage curve 160 of the three detectors 100, 101 and 102 acting in unison would be the resultant of the superposition of the plate current-grid voltage curves 150, 151 and 152 of the separate detectors, as

shown in Fig. 5, in which the characteristic resultant curve 160 is plotted from the straight lines 161 and 162 meeting in the form of a right angle, and along one of which, 161, grid voltage is measured, and along the other of which, 162, plate current is measured.

From the foregoing, it is evident that in this improved system shown in Fig. 3, and just described, a much wider current variation in the plate or controlled circuit through the receiving device 130 is possible than in the ordinary arrangement shown in Fig. 1 in which the receiving device 22 is controlled 15 by a single detector, and that the difference between the maximum current possible and the minimum current obtainable in the controlled circuit including the receiving device 130 of this improved system, depends upon 20 and is directly proportional to the number of detectors 100, 101, 102 utilized in the system to control the receiving device 130. It is also evident that by increasing the 25 number of detectors this difference between the limits of the current strength in the plate or controlled circuit may be proportionally increased, and that by using a suitable number of detectors arranged as shown in Fig. 3, the capacity of the system may 30 be so enlarged that it will be able to absorb powerful interfering signals from a nearby station without becoming "saturated" or "smothered" and without having the controlled circuit 129, 130 and 131 including 35 the receiving device 130, become consequently unresponsive to the weaker signals from the distant control station.

In the modified form of this invention shown diagrammatically in Fig. 6, instead of having a plurality of detectors, for instance, three, arranged as shown in Fig. 3 and as hereinbefore described, the system is arranged to be controlled by a multiplex detector 200 comprising a single evacuated 45 glass container 201 within which is arranged a plate 202, a grid 203 and a plurality of filaments, for instance, three, 204, 205 and 206. This multiplex detector 200 is arranged to be controlled by a closed oscillatory circuit 210, which includes a variable condenser 211, and a coil 212. The coil 212 forms the secondary coil of a transformer 213 which includes a primary coil 214 connected in series with an antenna 215 which is grounded through the coil 214 at 216. One end of the secondary coil 212 is connected by a conductor 220 to the grid 203, and the other end of the secondary coil 212 is connected by a conductor 221 with one end of the first 50 filament 204, which in turn is connected by a conductor 225 to one pole of a battery 226, the other pole of which is connected by a conductor 227 to one end of the second filament 205. The second filament 205 is 55 connected by a conductor 228 with one pole

of a battery 231, the other pole of which is connected by a conductor 232 to one end of the third filament 206. The filament 206 is connected by a conductor 235 with one pole of a battery 236, the other pole of 70 which is connected by a conductor 237 with one side of a closed oscillatory circuit 238, which includes a primary coil 239 and a variable condenser 240, and the other side of which is connected by a conductor 241 to 75 the plate 202 of the multiplex detector 200. The three filaments 204, 205 and 206 are arranged to be heated in a well known manner by three batteries 242, 243 and 244 acting respectively through rheostats 245, 246 and 80 247. The coil 239 forms the primary of a transformer 250, which has a secondary coil 251 arranged in a closed oscillatory circuit 252 which includes a variable condenser 253. The closed circuit 210 which controls the detector 200 may be tuned to the natural frequency of oscillation of the open aerial circuit 215, 214 and 216, and the closed circuit 238, which is controlled by the detector 200, 85 may be tuned to a predetermined secondary 90 frequency. The closed circuit 252 may also be tuned to respond to the predetermined secondary frequency, and may be arranged to control a further detector or detectors or other devices forming a selective system constructed in any well known or suitable manner.

In this modified system, any suitable receiving device might be substituted for the two closed circuits 239 and 252 controlled 100 by the detector 200.

In the operation of the modified system shown in Fig. 6, the characteristic plate current-grid voltage curve of the detector 200 would be approximately the same as 105 shown by the curved full line of Fig. 5, and the results obtained through the use of this modified system would be similar to the results obtained by the use of the system shown in Fig. 3 and hereinbefore described. 110

In the modified form of this invention shown in Fig. 7, the construction is the same as that shown in Fig. 6, except that instead of the plurality of filaments 204 and the corresponding plurality of batteries, a single elongated filament 255 is provided which is arranged to be heated by battery 256 through a rheostat 257. One end of the filament is connected by a conductor 258 to one pole of a battery 259, the other pole of which is connected by a conductor 260 to one side of the hereinbefore described closed oscillatory circuit 238. By having the filament 255 of a considerable and suitable length and of a suitable resistance, the normal heat current from the battery 256 in passing through the filament 255, will cause a predetermined drop in potential between one end of the filament and the other end of the filament, so that the different portions 130

of the filament will be normally maintained at predetermined and appreciably different potentials.

In the operation of the modified form of this invention shown in Fig. 7, the results obtained would be similar to the results obtained in the systems hereinbefore described, and a much more powerful impulse of radiant energy would be required to smother or saturate the improved detector than would be required where only a single detector of the ordinary form having a comparatively short filament, is used, and where the difference in voltage between the two ends of the filament is correspondingly small.

The ordinary audion or detector filament at its working temperature has a potential drop along its length of approximately two volts. The long, single filament hereinbefore described might at the proper temperature have a potential different of from six to ten volts between its terminals.

It is obvious that the means for postponing saturation herein described would be equally effective if the familiar stoppage condenser were employed in each of the grid leads of the audions.

Although only three forms have been shown herein in which this invention may be embodied, it is to be understood that the invention is not limited to any specific construction, but might be embodied in various systems without departing from the spirit of the invention or the scope of the appended claims.

Having thus fully described this invention, I claim:

1. A receiving system for radiant energy, comprising a receiving device, and a circuit for controlling said device, including two conductors and a plurality of detectors connected in parallel between said conductors, and a closed oscillatory circuit responsive to radiant energy and arranged to simultaneously control said detectors each of said detectors including a container and ionizing means, means for increasingly varying the potential of the input circuit of each successive detector and a third electrode in said container.

2. A receiving system for radiant energy, comprising a receiving device, a circuit for controlling said device including two conductors and a plurality of gaseous detectors connected in parallel between said conductors, and a closed oscillatory circuit responsive to radiant energy and arranged to simultaneously control said detectors each of said detectors including a container

and ionizing means, means for increasingly varying the potential of the input circuit of each successive detector and a third electrode in said container.

3. A receiving system for radiant energy, comprising a receiving device, and means responsive to radiant energy for controlling said receiving device, including a closed oscillatory circuit provided with a condenser, two conductors leading from the opposite sides of said condenser respectively, and a plurality of detectors connected in parallel between said conductors each of said detectors including a container and ionizing means, means for increasingly varying the potential of the input circuit of each successive detector and a third electrode in said container.

4. In a receiving system for radiant energy, a receiving circuit responsive to received radiant oscillations, an indicating device and a plurality of three-electrode thermionic tubes each having input and output elements, said tubes having their output elements connected to said indicating device, and means for applying progressively greater differences of potential to the input elements of the successive tubes.

5. In a receiving system for radiant energy, a receiving circuit responsive to received radiant oscillations, thermionic tube detecting means including an output circuit, a plurality of cathodes connected in parallel in the output circuit and means for controlling the passage of current through the detecting means in accordance with the received radiant oscillations, means for applying progressively varying differences in potential between the successive cathodes and said controlling means, and indicating means controlled by the output circuit.

6. In a receiving system for radiant energy, a receiving circuit responsive to received radiant oscillations, thermionic tube detecting means including an output circuit, a plurality of cathodes connected in parallel in the output circuit and means for controlling the passage of current through the detecting means in accordance with the received radiant oscillations, sources of potential interposed between the cathodes for applying progressively greater differences in potential between the successive cathodes and said controlling means, and indicating means controlled by the output circuit.

Signed at New York in the county of New York and State of New York this 16th day of October, A. D. 1917.

JOHN HAYS HAMMOND, JR.
